Peter R. Laudi, 9310 Behrwald Ave., Brooklyn, Ohio

Filed Jan. 9, 1963, Ser. No. 73,097

Term of patent 14 years

(Cl. D72—1)

FIG. 1

FIG. 2

FIG. 3

FIG. 1 is a front elevation of a hand safety signal embodying my new design;

FIG. 2 is a side elevational view thereof; and

FIG. 3 is a top plan view thereof.

The opposite side of FIG. 1 is substantially the same as the side shown.

The dominant features of my design reside in the portions shown in full lines.

I claim:

The ornamental design for a hand safety signal, substantially as shown and described.
